UNITED STATES PATENT OFFICE.

JACOB HENRY POSTEL, OF SAN MATEO, CALIFORNIA.

SPRINKLER-HEAD GARDEN-TOOL.

1,264,556.

Specification of Letters Patent. Patented Apr. 30, 1918.

Application filed July 25, 1917. Serial No. 182,781.

To all whom it may concern:

Be it known that I, JACOB H. POSTEL, a citizen of the United States, residing at San Mateo, in the county of San Mateo and State 5 of California, have invented a new and useful Sprinkler-Head Garden-Tool, of which the following is a specification.

The subject of this invention is a sprinkler head garden tool in which a grubbing or 10 cultivating head is arranged to be utilized in watering, and the objects of the invention are, first to provide a combined sprinkler head and garden tool, second to provide a sprinkler head which will direct water in 15 various directions as desired, third, to provide a sprinkler head which may be connected in a variety of ways as occasion may demand, fourth, to provide a sprinkler head that may be readily anchored in place, fifth, 20 to provide a simple and efficient sprinkler head and garden tool.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 25 within the scope of what is claimed, without departing from the spirit of the invention.

A practical embodiment of the invention is shown in the accompanying drawings, 30 wherein:

Figure 1 is a side elevation of a sprinkler head constructed in accordance with this invention.

Fig. 2 is a central vertical section.

40 Fig. 3 is a head end elevation.

Fig. 4 is a side elevation showing the head anchored in place.

Fig. 5 is a side elevation showing a method 45 of connecting the heads in a pipe line.

Fig. 6 is a view in elevation showing the heads as applied to a rotary sprinkler.

Fig. 7 is a view in side elevation showing a slight modification of the head.

50 Referring to the drawings by numerals of reference:

The sprinkler is substantially in the form of a T head the leg 1 of which forms the attaching nipple of the usual form, and in this 55 nipple adjacent the cross arms of the T a transverse slightly inclined bore 2 is provided which communicates with the longi-

tudinal bore 3 of the nipple. The bore 2 is 60 interiorly threaded to receive a needle valve 4 preferably provided with a wing head 5 by which it may be adjusted. The reduced end of the needle valve engages the usual 65 seat 6 and closes or controls the opening of discharge port 7.

One arm of the cross arm of the T is in 70 the form of a flattened blade 8, similar to a hoe blade, while the other arm of the cross arm is in the form of a cone producing a pick 9. As will be apparent, the bore 2 is inclined so that liquid discharged from the nozzle 7 will be directed against the flat blade 75 8 at an angle to deflect the liquid from the end of the blade.

The nipple is provided with exterior 80 threads 10 and interior threads 11 for the purpose of permitting pipes of different sizes to be attached to the head. A divided 85 collar 12 may surround the nipple 1 and have its ends bent to form lugs 13, apertured and threaded to receive a thumb screw 14 which serves to lock the collar in place about 90 the nipple. The thumb screw 14 may also pass through the eye of an anchoring pin 15 which is thus pivotally held between the turned ends of the collar 12.

As indicated in Figs. 1 and 2, a section of 95 pipe 16 may be attached to the head and serve as a handle when using the device as a garden tool or as a connection with a hose for watering.

In Fig. 5 the heads are illustrated as connected by T joints 18 in a pipe line 19 which is a convenience when a large area is to be watered; while in Fig. 6 application of the heads to a rotary sprinkler 20 is shown.

The modification shown in Fig. 7 is exactly 95 the same as the head heretofore described except that the longitudinal bore 2' of the head is continued all the way through the head and may be closed by a screw plug 17. As will be seen, this permits the heads 100 to be readily secured in a pipe line 19' and in position to spray the water upward.

The head may be used for cultivating around plants. A hose with water turned in being attached to the handle 16, the plants 105 can be readily watered by manipulating the needle valve. As the water is directed against the blade 8 and deflected from its end in a thin sheet or band, by properly holding the head this band of water may be 110 directed down a row of plants.

Having described the invention, what is

claimed as new and sought by Letters Patent, is:

1. A sprinkler head garden tool, comprising a **T** head, an attaching nipple forming part of the head and provided with a transverse inclined bore, and a needle valve working in the bore, one arm of the **T** forming a flat blade positioned to deflect liquid discharged from the bore.
- 10 2. A sprinkler head garden tool, comprising a **T** head, an attaching nipple forming the leg of the **T** head and provided with a transverse bore terminating in a discharge orifice, a needle valve in the bore and controlling the discharge from the orifice, and a flattened blade forming one arm of the **T**

head and positioned to deflect liquid discharged from the orifice.

3. A sprinkler head garden tool, comprising a **T** head, an attaching nipple forming 20 the leg of the **T** head, the opposed arms of the cross bar of the **T** forming a blade and a pick, and means for discharging liquid through the head against the blade to be deflected by the blade.

25 In testimony that I claim the foregoing as my own, I have hereto affixed my signature in the presence of two witnesses.

JACOB HENRY POSTEL.
